UNITED STATES PATENT OFFICE

ROSCOE D. CONKLIN, OF RAHWAY, NEW JERSEY, ASSIGNOR TO NATIONAL PNEUMATIC COMPANY, OF NEW YORK, N. Y., A CORPORATION OF WEST VIRGINIA

KNOCK-OUT SWITCH

Application filed April 6, 1929. Serial No. 352,965.

This invention relates to the provision of a novel knock-out switch structure for electric engines.

One of the objects of this invention is the provision of a switch which may be used for breaking the circuit of an electric door operating engine at the end of the door travel.

Another object of this invention is the provision of a switch which may be used for breaking the circuit on an electric door operating engine after movement of the door into opened or closed condition.

A still further object of this invention is the provision of a knock-out switch with means to provide, after the contact has initially been broken, an overrun feature which permits of the door motors coasting to a dead stop after breaking a circuit on the switch without any resulting jamming or damage to the switch parts.

A still further object of this invention is the provision of a quick return switch for use with electric door operating engines provided with means to return said switch to normally closed position.

Various other objects and advantages of the invention than those hereinabove mentioned will be specifically pointed out or will be apparent hereinafter in the course of the below detailed description of the form of the invention shown in the accompanying drawings, as preferred ones of the various possible embodiments of the invention; it being understood, naturally, that such forms are

merely illustrative of some of the many possible combinations and arrangements of parts well calculated to attain the objects of the invention, and hence said detailed description of such form is not to be taken as at all times defining or limiting the invention itself. That is to say, the scope of protection contemplated is of course to be taken from the appended claims interpreted as broadly as is consistent with the prior art.

In the accompanying drawings,—

Figure 1 is a top plan view of my novel switch structure;

Figure 2 is an elevational view thereof.

Similar reference characters refer to similar parts throughout the several views of the

drawings. The invention resides substantially in the construction, combination, arrangement and relative location of parts, all as will be more fully indicated hereinafter.

It is the purpose of this invention to provide a switch that may be used for breaking the electric circuit on an electric door operating engine at the end of the travel of a railway car door, when said door has reached either end of its travel. One of the results accomplished by the novel structure hereinafter described in detail is the allowable overrun that this switch permits. In other words, the door motor is permitted to coast to a dead stop after the circuit is broken on the switch which carries the contact arm with it, said contact arm having been connected to said motor by means of mechanical levers, and to do so in such a fashion that no jamming or damage results to any parts of the switch or mechanical levers. It is also the purpose of this invention to provide a switch accomplishing the foregoing objects which when opened or closed provides a rolling and sliding contact action which assists in keeping the contact surface clean. Although the switch will be hereinafter described as intended primarily for use with electric door operating engines, it is obvious that the structure disclosed permits of collateral use for other purposes, in any circuit where it may be desired to make and break the circuit rapidly with provision for a quick return of the return to a neutral position.

The engine on which the switch hereinafter described may be used is not shown inasmuch as said switch may be used with any standard type of prior art engine and the adoption of said switch to such an engine is but one use of such switch, many others which will be apparent to those skilled in the art.

Referring specifically to the drawings, it will be seen that 1 is a base of some suitable insulating material on which are mounted the contact members 2, 2 at either end thereof. Passing through said insulating base is the arm 3' which may be connected via a set of mechanical levers to a door operating engine (not shown). When the lever 3' is pushed to the right contacts 3 and 4 mount-

ed on the hinged arm 5 will be raised when the portion 6 on the engaging lever 7 rotating about the center of the shaft 8 comes into contact with such arm. This breaks the contact at the two contact points 9 and 10. Lever 6 has two arms projecting under hinged levers 5 and 11 and will lift either 5 or 11 according to the direction of rotation of the handle 3' on the shaft 8. If the arm 5 is lifted the arm 11 apparently will remain stationary. The spring 12 tends to hold the two contact groups 3, 4, and 13, 14 onto their respective contact points at all times except when the lever 3' is rotated to the right or left, according to the circuit it is desired be broken. Contacts 3, 4, 13 and 14 are against their corresponding contact points under the tension of springs 15 and the action produced thereby when a whole contact arm is raised or lowered by actuating the lever 3' is a slightly rolling or sliding contact, which assists in keeping the contact surface clean. The base 1 as before specified is of some suitable insulating material and is provided with means, such as arms 16 in which are prelocated holes 17, for mounting said structure.

Mounted in each of the arms 5 and 11 are pieces of insulating material 18 adapted to insulate the lever 3' which is connected via various levers back to the door operating motor and to prevent possible short circuits due to any inadvertent grounding effects taking place. By means of the provision of the spring element 12 and the various spring elements 15 I accomplish what I call the overrun feature which consists in permitting the motor to coast to a dead stop without any jamming or breaking of parts after the contact has been initially broken. This is attained by the use of the hinged levers in coaction with the springs which permit of said levers being raised to a suitable height against pressure of the opening 12.

It is obvious, due to the construction of this switch that pressure is taken away from either side of the lever 3 the spring pressure of 12 will return both sets of contacts to a making position and levers 3 will assume a central or neutral position, as is shown in the drawings, Figs. 1 and 2.

Inasmuch as many changes could be made in the above constructions and many apparently widely different embodiments of the invention could be made without departing from the scope thereof it is intended that all matter contained in the above description or shown in the accompanying drawings shall be interpreted as illustrative and not in a limiting sense. It is also to be understood that the language contained in the following claims is intended to cover all the generic and specific features of the invention herein described, and all statements of the scope of the invention, which as matter of language or

philologically speaking might be said to fall therebetween.

I claim:

1. In a switch structure, substantially of the type described a support, a plurality of contacts mounted on said support, an actuating arm mechanically passing through said support, switch arms on said support adapted to actuation by said arm, means to cause said switch arms to normally close circuits through said contacts, means carried by said actuating arm for selectively effecting said switch arms and means providing a wiping and rolling action on the opening or closing of said circuits. 70

2. The structure recited in claim 1, characterized in this, namely that two arms carried by said actuating arms project under hinged levers and are adapted to lift said hinged levers according to the direction of rotation of the actuating arm to actuate said contacts. 85

3. In a switch an insulating body, a pivot, a plurality of levers pivoted on said pivot and an actuating arm pivoted thereon and projecting through the insulating body, contact elements mounted on said body, means carried by said arm to actuate said levers, contact arms carried by said levers, and means tending to normally force said contact arms into contact with said contact elements. 90

4. In a switch an insulating body, a pivoted actuating arm projecting therethrough, contact elements mounted on said body, hinged levers having a common pivot mounted on said body, means carried by said arm to actuate said levers, contacts arms carried by said levers, and means carried by said contact arms and hinged levers to provide a wiping and rolling action by the contact elements on opening of the contacts. 100

5. In a switch an insulating body, a pivoted actuating arm projecting therethrough, contact elements mounted on said body, hinged levers mounted on said body, means carried by said arm to alternately actuate said levers, bridging contact arms carried by said levers and means including a single resilient element carried by said levers tending to normally force said contact arms into contact with the contact elements. 110

6. In a switch an insulating body, a pivoted actuating arm projecting therethrough, contact elements mounted on said body, hinged levers mounted on said body, means carried by said arm to alternately selectively actuate said levers, bridging contact arms carried by said levers, resilient means carried by said levers tending to normally force said contact arms and hinged levers to provide a wiping and rolling action at the contact elements on opening of the contacts. 120

7. In a switch substantially of the type described a plurality of contact arms having a common pivot, a plurality of contacts, means

5 tending to normally force said arms into contact with said contacts to close a plurality of circuits, means including a rotatable mounted lever to alternately open one set of said contacts, and means to provide a sliding and wiping action upon operation of said contact operating means.

6 8. In a switch substantially of the type described two sets of bridging contact arms, 10 means tending to normally bring both sets of bridging contact arms into contact with their respective contacts, and means including a rotatable lever and a cam shaft element to selectively open one of said sets of contacts.

15 9. In a switch substantially of the type described a plurality of contacts, a plurality of contact arms, a single spring tending to normally cause said contact arms to contact with said contacts, hinged levers on which said 20 contact arms are mounted, an actuating lever, means carried by said actuating lever to actuate said hinged levers to selectively lift said contact arms.

10. In a structure substantially of the type 25 described an insulating member, an actuating arm projecting therethrough, two sets of hinged levers mounted on a common pivot thereon, a plurality of contact elements mounted thereon, contact arms carried by 30 said hinged levers, and means carried by said actuating arm to selectively actuate a single one of said sets of hinged levers.

11. The structure recited in claim 10 characterized in that resilient means are carried 35 by said contact arms and hinged levers to provide a sliding, rolling and wiping action upon opening of the contacts.

12. In a switch structure substantially of the type described, a plurality of sets of 40 bridging contact arms adapted to quick operation, a plurality of contacts, means tending to normally close said contact arms on said contacts, means adapted to selectively open electric circuits connected to each set of 45 contact arms, and means including a resilient element to provide a wiping and rolling action at the contacts upon the opening and closing thereof.

13. The structure recited in claim 12 in that 50 the contact arms are selectively actuated by an actuating arm mounted on and projecting through an insulating base, which arm carries a cam shaft member.

55 14. In a switch structure substantially of the type described, an insulating base, a plurality of contacts mounted thereon, a rotatable actuating lever mounted on and projecting through said base, a plurality of hinged 60 levers having a common pivot and adapted to actuation by said arm, means carried by said actuating arm to selectively actuate said levers, contact arms carried by said hinged levers which are adapted to contact with said 65 contact elements, and means tending to nor-

mally close said contact arms on their contacts.

15. In a switch substantially of the type described, a plurality of sets of contact arms, means tending to normally bring all of said sets of contact arms into contact with their respective contacts, and means including a pivoted actuating element and a cam shaped element to selectively open a single one of said sets of contacts. 70 75

In testimony whereof I have hereunto set my hand on this 1st day of April A. D., 1929.

ROSCOE D. CONKLIN.
